UNITED STATES PATENT OFFICE

91,840

DESIGN FOR A HEATING PAD

George A. Proctor, Los Angeles, Calif., assignor
of one-half to G. H. Hyland, Los Angeles,
Calif.

Application January 15, 1934, Serial No. 50,401

Term of patent 14 years

To all whom it may concern:

Be it known that I, GEORGE A. PROCTOR, a citizen of the United States, residing at Los Angeles, in the county of Los Angeles and State of California, have invented a new, original, and ornamental Design for a Heating Pad, of which the following is a specification, reference being had to the accompanying drawing, forming a part thereof:

Fig. 1 is a front elevation of a heating pad showing my new design;

Fig. 2 is a perspective view thereof.

I claim:

The ornamental design for a heating pad, as shown.

GEORGE A. PROCTOR.
